PRINTING MACHINE

Blackwell K. Murchison, Brooklyn, N. Y.

Application October 9, 1937, Serial No. 168,138

39 Claims. (Cl. 101—35)

The invention relates to printing machines, and more particularly to a machine including therein a plurality of type carrying members, and means by which succeeding lines of type may be set up, an imprint may be made following the setting of each line of type, and the types from which imprints have been made, may be distributed preparatory to the setting up of a succeeding line.

10 In a machine embodying the invention, the various type carrying members of the printing couple are equipped with a complete fount of type, and means are provided whereby different letters and characters may be successively brought into alignment in the printing position in relation to a platen, and following the setting up of each line, the words may be spaced and the line justified prior to the making of an imprint therewith.

20 The word spacing and line justifying mechanism embodies therein selectively operative means carried by the several type carrying members, each of these individual mechanisms being capable of being set when type has been set for each word, all of such mechanisms remaining inoperative until a whole line has been set, whereupon the mechanisms so set may all be actuated from a single source of power so as to impart movement to all type carrying members necessary to effect a spacing of all of the words in the line, and bring the letter or character at the right hand end of the line into a position where it will, in the imprint, be in true vertical alignment with the corresponding characters of other lines. In other words, by the word spacing and line justifying mechanism of the invention, a corresponding margin is secured at each end of every line, thus securing an accurate column effect as with ordinary printing.

30 The construction and operation of the word spacing and line justifying mechanism is such that in the event of variation in the number of words, or the number of letters in a line, or both, the spacing between words will be automatically varied so as to equalize the movement of the various type carrying members in a manner to distribute the aggregate movement of all type carrying members amongst the spaces between different words.

40 The type carrying members are so constructed and arranged that they may be individually and successively actuated, and each member, after it has been actuated, will be locked in a set position, succeeding printing characters being brought by the type setting mechanism into substantial

alignment with characters previously set, and held against movement when setting succeeding characters, by this locking mechanism. The construction must be such that the setting member operative upon the type carrying members will be disengaged from each such member after each character has been properly set, in order to permit a proper progression in the setting up of type.

5 In connection with the type setting mechanism, I provide a proofing mechanism by means of which an impression is made of each character as it is set, so that preparatory to the actuation of the word spacing and the line justifying mechanism, the operator may determine whether or not the proper characters have been set up. This proofing mechanism is actuated simultaneously with, and by the same mechanism used for, actuation of the setting and locking mechanisms, and following the setting of a character upon each type carrying member.

25 The construction of the machine is such that when each line has been set up, and justified, and the type carrying members locked, an impression is made of that line, the printing operation being of the type known as bed and platen printing in which an impression platen is moved by a powerful mechanism into and out of engagement with the said types. Ordinarily, this impression is an ink impression upon a sheet of paper, 30 an inking mechanism being provided in the machine which is actuated by the platen operating mechanism in a manner to ensure a proper timing in the inking of the types and the making of an impression.

35 The particular inking mechanism shown is described in my co-pending application, Serial No. 146,175, filed June 3rd, 1937. If desired, however, stencil sheets may be used, in which case the application of ink to the types is not required. 40 Whether the machine is used for making an ink impression upon paper or for cutting a stencil, it is essential to provide a sheet feeding mechanism in operative relation to the printing platen, and to so actuate this mechanism as a result of the movements of the platen carrying member, as to secure an automatic feeding of the sheet and a proper spacing of succeeding lines upon the paper or stencil sheet. This feeding mechanism is so constructed as to permit great nicety 45 in the spacing of lines, and may be so set as to vary the line spacing to adapt the machine to work of different character.

50 To compensate for slight lost motion which may develop in the locking and alining mech-

anisms for the various type carrying members, I preferably provide a supplemental locking and alining bar actuated by the platen mechanism immediately prior to, and during the making of an impression.

- 5 Following the making of each impression, it is necessary to distribute the printing characters or types. To permit this, it is essential that the setting, and the locking and alinement members 10 be made inoperative as to each of said type carrying members, and that means be provided whereby a differential movement may be imparted to each type carrying member to restore it to a normal or zero position, so that when setting 15 up the next line of type, each type carrying member will occupy the same relation to the type setting mechanism as when setting up every other line.

The construction of this distributing mechanism is such that it may be brought into the operative relation to all of the type carrying members, so that finally, by a single continuing movement, all of these members will be brought into the desired position, with similar printing 20 characters upon all of said members in alinement. This is essential because the same actuating mechanism and an associated index is used for setting each type carrying member, and the extent of movement of each member to set up a given character must be the same as that of 25 every other member in setting up the same character.

The machine may also include type cleaning rollers which may be brought into or out of the operative relation to the printing characters to 30 facilitate the cleaning of the types.

The machine of the invention is designed to provide an original imprint, whether in ink or upon a stencil sheet, which may be used for reproduction purposes. If an inked impression is made, a printing plate is made from the sheet by ordinary photo-engraving methods with a suitable reduction to secure a desired sharpness of lines and strength of impression from the 40 photo-engraved plate. The machine ordinarily would be used in making an original for the production of such photo-engraved plates, oversized types being used to facilitate photographic reduction in the manner above referred to.

45 The construction of the machine is such as to permit accuracy in the setting up of the printed matter, rather than speed. All of the mechanisms are so constructed and arranged that in the event of error in setting up the printing characters, such error may be detected from the proof strip prior to the making of an impression, so that correction can be made or the line entirely re-set.

In the embodiment of the invention shown in 50 the drawings, a sequence of discs, each carrying a full fount of printing characters, is mounted upon the same shaft, and the setting of the printing characters and the setting and actuation of the word spacing and line justifying mechanism is accomplished by means carried by this shaft, but differentially operative to secure the desired progression in setting up a line of type.

55 The setting means for the various type carrying members is capable of connection with, or disconnection from, the alining and locking bar so as to ensure the proper alining and locking of successive type carrying members as they are set, while permitting the disengagement of this

locking bar from said members during the distributing operation.

The various mechanisms in the machine are so designed and so combined as to not only ensure certainty and reliability in the operation of these mechanisms to reduce error in the operation of the machine to a minimum, but these mechanisms are few in number and conveniently accessible to the operator so as to permit the operation of the machine at moderate speeds.

10 The invention consists primarily in a printing machine embodying therein the novel features of construction and combination of parts herein-after set forth and described, and more particularly pointed out in the claims hereto appended.

15 Referring to the drawings,

Fig. 15 is an illustrative view showing the various type carrying members set and ready for word spacing and line justifying;

50 Fig. 16 is a view similar to Fig. 15 showing the words in a line spaced and the line justified;

Fig. 17 is a detail view of the setting bar feed mechanism;

55 Fig. 18 is a plan view, partly in section, showing the setting wheel, its locking mechanism and the proofing mechanism;

Fig. 19 is an end view from the right of Fig. 18, partly in section and partly broken away;

Fig. 20 is a detail sectional view of the proofing hammer;

Fig. 21 is a detail view of the proof tape and its guide;

Fig. 22 is a front elevation of the mechanism shown in Fig. 18;

70 Fig. 23 is a perspective view of the actuating mechanisms for feeding the proof tape and for actuating the proofing hammer;

Fig. 24 is a detail perspective view of the distributing mechanism at rest;

Fig. 25 is a detail end view of the distributing mechanism, partly broken away, and set for the initial operation of this mechanism, the first stage of the operation of the distributing mechanism being shown in dotted lines; and

Fig. 26 is a view showing the distributing mechanism, the normal inoperative position of parts being shown in full lines, and the position of the parts upon the completion of the distributing operation being shown in dotted lines.

Like numerals refer to like parts throughout the several views.

In describing the various mechanisms of the machine, these mechanisms will be considered in the order of the sequence of operations of the machine, as follows: the type carrying members and the setting mechanism operative thereon; the word spacing and line justifying mechanism; the proofing mechanism; the printing mechanism; the distributing mechanism, and the type cleaning attachment. Various actuating parts in the machine, as shown in the accompanying drawings, are common to different mechanisms, and the movements of different parts will vary according to the mechanisms, the operative effect of which is controlled at different times during the setting up and distributing of a line of type.

Mounted in suitable bearings 30 and spaced from the bed 31 of the machine is a main actuating shaft 32, having idly mounted thereon a plurality of type carrying members 33, each of which, in the embodiment of the invention shown in the drawings, consists of a disc idly mounted upon the shaft 32 and having, about the periphery thereof, raised platens having engraved, rolled or otherwise impressed thereon, upper and lower case printing letters, numerals, punctuation marks, etc. Each disc carries a full fount of type, these types being selectively brought into the printing position as each disc is set, and the different discs being successively actuated by a setting mechanism and held in this position by a locking and alining mechanism after it is set, so as to avoid displacement of any type already set during succeeding operations of the machine in setting other types.

The various discs 33 are mounted in close abutting relation to each other, but are capable of separation in word spacing and in line justifying, by mechanisms carried by the various discs, which will be described in connection with the word spacing and line justifying mechanisms in the machine.

Each disc has a central bearing opening engaging the shaft 32, and extending outwardly of this bearing opening is a keyway 34 by means of which the disc may be turned when setting the type.

The main shaft 32 is provided with a sequence of longitudinally extending keyways 35, in one of which is slidably mounted a setting bar 36, a high part 37 of which is adapted to enter the keyways 34 of the several discs 33, and a low part 38 of which is of a height to be flush with the surface of the shaft 32. In this manner, the setting bar may be progressively disengaged from the sequence of discs 33 so as to permit the progressive setting of different type carrying members. In other words, the setting bar 36 is adapted to be selectively and progressively engaged with, and disengaged from, the various type carrying members so as to impart movement thereto with the turning of the shaft 32, or to permit turning of said shaft without imparting movement to type carrying members already set.

The shaft 32 is turned by means of a setting wheel 39 having about the periphery thereof, printing characters 40 corresponding with those upon the various type carrying members, there being associated with this wheel, an index finger 41 by means of which accuracy in the movement of the wheel to bring the desired character in the printing position, may be secured. The position of the index characters 40 upon said wheel 39 is approximately 180° offset in relation to the corresponding characters upon the several discs 33.

The edge of the hand wheel 39 is provided with a sequence of notches 42 with which a lock member 43 is adapted to co-operate following the setting of each disc.

The setting bar 36 is carried by a sleeve 44 slidably mounted upon the shaft 32 and capable of a step by step movement along this shaft as the setting of the various type carrying members progresses. This sleeve 44 carries a ratchet tooth member 45 by which the sleeve and the bar 36 may be advanced by a reciprocatory ratchet bar 46, spring pressed by a plunger 47 into engagement with the ratchet tooth member 45. This spring plunger support for the ratchet bar 46 permits the teeth of this bar to ride over the teeth of the fixed pawl 45 during its return movement following each feeding movement of the sleeve 44.

The ratchet bar 46 has, in the side thereof, a groove 48 in which is seated a crank pin 49 carried by a shaft 50 having a knurled head, so that when restoring the setting bar 36 to its operative relation to all of the discs 33, said bar may be disconnected from the member 45. This return movement of the sleeve and said bar is by means of a cord 51 passing about guide pulleys 52 and 53 and about an actuating sheave 54 having a crank handle 55, the opposite ends of this pull cord being connected at opposite faces of the sleeve 44.

The sleeve 44 merely slides along the shaft 32, this shaft and the setting bar 36 having turning movement in said sleeve. To secure this result, I provide the sleeve 44 with a bearing collar 56, the angular end of the setting bar 36 being secured to this bearing, as indicated at 57 in Fig. 4 of the drawings.

Since the low part 38 of the bar 36 is flush with the surface of the shaft 32, said shaft, the collar 56 and the portion 38 of the setting bar may turn freely in relation to the sleeve 44.

Mounted in a suitable bearing 58 is a shaft 59, Fig. 2, actuated by a crank handle 60. This shaft 59 carries an eccentric pin 61 seated in a pocket 62 adjacent one end of the ratchet bar 46. By turning the shaft 59 alternately in clockwise and contra-clockwise directions, said bar 46 will be reciprocated to advance the sleeve 44 and the setting bar 36 longitudinally of the main shaft 32.

Mounted in suitable guides 63 is a locking and alining bar 64 adapted to enter the spaces between the platens upon the several type carrying members 33. Said guides 63 are carried by the top plate of the machine directly below the vertical center of the shaft 32 and of the various discs 33 mounted thereon.

While the high part 37 of the setting bar 36 is normally engaged with discs 33 which have not been set, the locking and alining bar 64 is normally disengaged from all of the discs 33 which have not been set, but is so actuated as to successively engage each disc after it has been set. With movement of the sleeve 44 along the shaft 32, the setting bar is disengaged from

each disc after it has been set, and the bar 64 receives movement with said sleeve so as to engage those discs from which the setting bar 36 is disengaged, simultaneously with the disengagement of said bar therefrom.

It is essential, however, during the distributing operation, that both bars 36 and 64 be disengaged from the discs.

To secure the above desired mode of operation, the sleeve 44 is detachably connected with the bar 64 by means of a pendent lug 65 carrying a latch member 66 engageable in a keeper slot 67 upon said bar 64. The shaft 50, as shown in Fig. 14, is mounted in this lug, and the latch member 66 is spring pressed into engagement with the locking and alining bar. Said bar 64 is provided with a finger grip 68 by which longitudinal movement may be imparted to this bar when the latch member 66 is disengaged therefrom.

A machine embodying the invention is used for setting one line of type of a predetermined length, at a time, and making an impression from that line of type prior to the distribution of such type and the setting up of succeeding lines in the same position as the previous line.

In hand or machine setting of type, or matrices from which a line of type may be cast, quads or other word spacers are used when setting up the type or in justifying the line, so as to have all lines of exactly the same length. Quads and other spacers are also used in correcting errors in hand setting up of type, and in justifying lines of type when so corrected. Conforming the set up of type to a corrected proof and rejustifying lines is a time consuming procedure, and in some instances may require the re-setting of several lines of type where words have to be omitted, added, shortened or lengthened.

The machine of the invention sets only one line of type at a time, so that in the event of error, a necessary re-setting will be limited to a single line, or to only a part of that line. While, in ordinary type setting methods, quads or other word spacers are used following each word, and additional spacers used when justifying a line which is completely set up, by the machine of the present application no spacers need be used, and word spacing and line justification is secured by a single operation of the machine after a line has been completely set up.

During the setting of a line of type, a word spacing and line justifying mechanism may be set, preparatory to its actuation, and following the setting of the last type carrying member of a word, and the various spacing and line justifying mechanisms so set are simultaneously actuated when the line has been completely set, so as to impart movement to all type carrying members longitudinally of the shaft 32 to an extent to bring the last letter of the line to the extreme right of a column impression. The amount of movement of the various type carrying members will differ in lines having a different number of letters or a different number of words, but the word spacing and line justifying mechanism will automatically distribute the maximum available movement throughout the spaces between the words by varying the quantity of movement of the type characters.

To secure the above mode of operation, each of the type carrying members 33 has a recessed portion 69 in one face thereof, about which are a plurality of guide clips 70, by means of which

a flat pawl ring 71 is mounted within the recess.

About the outer periphery of the pawl ring 71 is a cam surface 72, engageable with the adjacent guide clip 70. A second double acting cam 73 is acted upon by a spring 74 to hold the pawl ring 71 off-center in relation to the shaft 32 and engage the cam surfaces 72 with said clip 70. This pawl ring also carries a stop 75 limiting the turning movement of the ring by engagement with one or the other of two adjacent guide clips 70. This pawl ring also has a recess 76 through which the setting bar 36 passes, the high part 37 of said bar being adapted to engage the walls of said recess. The ring 71 is adapted to be turned by the main shaft 32 through the application of power from this shaft to oppositely set pawls 77-78 carried upon said ring 71, these pawls being drawn toward each other and permitted to move away from each other by a spring 79 acting between the two pawls.

The disc 33 about the recess 69 is provided with three cam surfaces 80 spaced approximately 120° apart, adapted to cooperate with bearing shoes 81 carried by spring arms 82 fixed to the pawl ring 71. The guide clips 70, the pawl ring 71, the pawls 77-78 and the spring arms 82 are all within the plane of the face of the disc having the recessed portion 69, so that the adjacent discs can be brought into closely abutting relation, as shown more particularly in Figs. 8 and 9 of the drawings. The shoes 81 are of a thickness to separate adjacent discs as they slide along the cam surfaces 80 with turning movement of the ring 71.

The spring 74, with a normal setting of the ring 71, holds this ring off-center in relation to the shaft 32 with the pawls 77-78 out of engaging relation with said shaft. If said pawl ring 71 be turned very slightly in a clockwise direction, as shown in dotted lines in Fig. 10, the cam surface 72, by engagement with its co-operating guide clip, will impart movement to the ring 71 substantially radially of the shaft 32, so as to permit the spring 79 to act to engage the pawls 77-78 with the periphery of the shaft 32.

As heretofore stated, this shaft has a plurality of longitudinally extending grooves 85 along the portion thereof upon which the various type carrying members are mounted, which grooves extend to the extreme right hand end of the shaft, as shown in Fig. 4.

To prevent the pawls 77-78 from entering these grooves with the turning of the ring 71 in the manner indicated, I provide a plurality of filler bars 83 slidably mounted in said grooves, which filler bars will be engaged by the pawls 77-78 with the turning of the pawl ring 71. Said filler bars are carried by a head 84 to which is connected a rack bar 85, said rack bar and said head being connected by a swivelling fitting 86, as shown more particularly in Fig. 6 of the drawings.

Carried by the bed of the machine is a bracket 87 (see Fig. 2) in which is mounted a shaft 88 carrying a gear wheel 89 enmeshed with the spacing and justifying rack bar 85. The shaft 88 has a hand crank 90.

The various discs 33 are positioned between headers 91 and 92, both of which are idly mounted upon the shaft 32. The header 91 has no movement along the shaft 32, but the header 92 is slidably along said shaft and carries a plu-

rality of stop rods 93 engageable with a stop member 94 adjustably mounted upon the bracket 87. This bracket is adjustable toward and from the header 92 in order to permit variation in the movement of the type carrying members, according to the number of words and letters in a line. Gauge markings, shown in Fig. 2 of the drawings, are used to facilitate the adjustment of this stop member.

To permit the movement of the pawl ring 71 in the manner above referred to, it is essential that the high part 31 of the setting bar 36 be brought successively into engagement with the keyway 34 of each disc 33 to be set and then moved out of engagement with said keyway and into a position where it may be engaged with the shoulders of the recess 16, so that the shaft 32 may be turned after the type carrying member has been properly set to actuate the ring 71 without disturbing the setting of the discs 33. In other words, a two-step movement is imparted to the setting bar 36 following the setting of one type carrying member, and preceding the setting of the next adjacent type carrying member. Consequently, since all movement of the setting bar 36 results from an actuation of the rack bar 46 by movement of the crank handle 68, it is necessary to give said handle two direct and return impulses after a type carrying member has been set and, upon the completion of the setting of each word, to turn the shaft 32 to set the pawls 77-78 after the first complete direct and return impulse of said handle, or between the impulses of said handle.

The stop member 94 is mounted in suitable guides 95 upon the bracket 87, and is provided with a lock screw 96 by which the stop may be set in any adjusted position.

The outside diameter of the ring 71 is considerably smaller than the diameter of the recess 33 in the disc, and the inside diameter of said ring is larger than the diameter of the shaft 32 and is provided with recesses for the accommodation of the pawls 77-78 and for a stop member 97 formed upon the disc 33 for limiting the first stage of movement of the disc by the setting bar 36. It is also provided with a curved enlargement 98 which, during the final stages in the turning of the ring, when the spreading heads 31 are operative, will engage the shaft 32. These, however, are mere matters of design necessary to permit the combined turning and radial movement of the rings as they are operated to set the pawls 77-78.

As heretofore pointed out, one line of type at a time is set up, and after an impression has been made therefrom, the type is distributed. Consequently, there is no standing type from which a proof can be pulled, and any typographical errors in setting up a line must be detected before the imprint is made from that line if the re-setting of all of the type in printing a sheet is to be avoided.

To permit detection of any typographical error in setting up the type, I provide a proofing mechanism which is actuated following the setting of each letter, so that the proof sheet or tape may be inspected prior to the making of an impression from that line and, if necessary, the whole line or a part thereof may be re-set to correct the error. By using a proofing mechanism which is thus progressively actuated, the operator may avoid error in the final set up and avoid much of that expense and delay which occurs in ordinary typographical work in cor-

recting proofs and conforming the set up to the corrected proof.

In the actuation of the proofing mechanism, some of the mechanisms used in setting the various type carrying members or discs 33 are utilized, thus ensuring accuracy in the operation of the proofing mechanism as well as a proper timing in the actuation of the same in relation to the setting mechanism.

The proofing mechanism, as shown in detail 10 in the accompanying drawings, consists of a guide 99 positioned adjacent the periphery of the setting wheel 39.

In addition to the printing characters 40 about the wheel 39 is a second set of printing characters 100, offset in their arrangement in relation to the characters 40, and so positioned in sequence that each printing character is brought into the printing position, a corresponding printing character will be positioned adjacent an opening 101 through the guide 99. A proofing tape consisting of a carbon coated strip 102 is positioned in the guide 99 toward the hand wheel 39, while another strip 103, separable from the strip 102, upon which impressions are made by means of the carbon strip, is presented toward the operator. The guide also has an opening 104 therein through which feed rollers 105 carried by a shaft 106 pass and engage the strip 103.

Pivotedly mounted adjacent the shaft 106 is 30 a bell crank lever 107 having one arm provided with a fork 108 carrying a proofing hammer 109, and the other arm of which is in the form of a cam 110. Acting upon this lever is a spring 111 having a normal tendency to force the hammer 109 toward the opening 101 in the guide 99. The shaft 106 receives intermittent rotation from a ratchet wheel 112 acted upon by a star wheel 113 carried by and rotatable with a ratchet wheel 114, the ratchet wheel having, in 40 the form of the invention shown, six teeth, while the star wheel 113 has three arms.

Carried by the crank arm 60 is a pawl 115 which, with oscillation of said arm 60, is engaged by a spring 116 with one of the teeth 45 of the ratchet wheel 114. Said ratchet wheel 114 receive one-sixth of a revolution with each downward movement of the crank handle 60, during which the star wheel 113 will actuate the shaft 106 in a manner to impart feeding movement to the proof tapes 102 and 103 by one arm of this wheel, and the succeeding arm of this wheel will act upon the cam 110 in a manner to move the hammer 109 away from the guide 99 and tension the spring 111, so that upon the succeeding downward movement of the crank arm 60, the hammer will be released while the tapes 102 and 103 are at rest, thus permitting the spring 111 to violently project the hammer into engagement with the tape 103 and cause 60 the making of an impression thereon in the manner indicated in Fig. 21 of the drawings. A detent spring 117 acts upon the ratchet wheel 114.

The proof hammer, as shown particularly in Fig. 20 of the drawings, consists of a plunger 109a 65 having a soft head 109b, which plunger is loosely mounted in a cylinder 109c. With this construction, rapid movement of the arm 108 will project the plunger 109a outwardly of the cylinder 109c with a speed sufficient to develop the desired 70 staccato blow upon the tape 103 when making a proof.

The shaft 59 is formed in two parts having a pin and slot lost motion connection shown more particularly in Fig. 18 of the drawings. The part 75

of this shaft carrying the eccentric pin 61 has mounted thereon a sleeve 118 carrying the crank handle 60 and acted upon by a torsion restoring spring 119. This sleeve carries a cam 120 acting 5 upon the locking tooth 43 engaging the teeth 42 upon the setting wheel 39. A spring 121 acts to normally disengage the tooth 43 from the teeth 42. The pin and slot lost motion connection is shown at 122.

10 A roll of proofing strip 102—103 is carried by a suitable reel 123 mounted adjacent the guide 99.

By the described construction of the shaft 59—118, the shaft 32 is locked against movement prior to any movement of the setting bar 36, and 15 the setting wheel 39 is held against possible accidental movement until after actuation of the proofing hammer.

The quantity of movement of the handle 60 may be regulated by set screws 124 engageable with a 20 crank arm 125 upon the handle 60.

After a line has been set up in the manner and by the mechanisms heretofore described, a proof has been made of all of the letters and characters in said line, and the words in the line have been 25 spaced and the line justified, an impression is made of this line upon a sheet of paper, or a stencil sheet as heretofore described. These lines are accumulated upon this sheet until a printed page of the desired size has been produced, where- 30 upon the completed sheet of paper is removed from the machine and a new sheet of paper is mounted in relation to the printing mechanism. The printing mechanism must therefore include not only an impression platen, but a cylinder ad- 35 jacent said platen for supporting and feeding a sheet of paper in relation thereto, and means for imparting a step by step feeding movement to the cylinder following each actuation of the platen to cause a proper spacing between suc- 40 ceeding lines impressed upon the sheet.

In conjunction with said platen and said paper supporting and feeding mechanism, I provide means whereby the amount of feeding movement of the sheet may be varied to secure different 45 spacings of the lines, and an actuating mechanism for the platen which will develop the proper pressure relation between the platen and the types, cause movement of the paper cylinder with the platen, and actuate this cylinder immediately 50 following the making of each impression.

The platen proper, as shown in Fig. 3 of the drawings, comprises a bar 126 mounted at each end thereof upon one arm 127 of a three armed lever, another arm 128 of which is pivoted to the 55 bed of the machine at 129. Mounted in said lever is a paper roller 130 having two clamp bars 131 and 132 adapted to engage the top and the bottom of the sheet respectively.

The cylinder 130 is loosely mounted upon a 60 shaft 133 and has secured thereto a ratchet wheel 134. Also loosely mounted upon said shaft 133 is a swing frame 135 carrying a plurality of pawls 136 engageable with the ratchet wheel 134.

Carried by the hub of the three armed lever is 65 an arm 137 having a spring 138 connected with the swing frame 135 so as to impart movement to this frame during the interval that the platen 126 is being advanced into engagement with the type from which an impression is to be made.

70 The swing frame 135 has one arm 139 provided with a stop screw engageable with the shaft 129 to limit oscillation of said frame in one direction, and with a second arm 140 carrying an anti-friction roller 141 engageable with a cam 142 ad- 75 justably mounted upon suitable guideways 143

upon the bed of the machine. This cam 142 is adjustable along said guides by a lead screw 144, and a lock screw 145 is provided for securing the cam in any adjusted position. A gauge cylinder 146 is carried by the lead screw 144, and adjacent 5 this gauge cylinder is an index finger 147 by means of which the extent of adjustment of the cam 142 may be determined with reasonable accuracy.

By means of the lead screw 144, the cam 142 may be advanced towards the bearing 129 to increase the spacing between succeeding impressions of lines of printed matter. By withdrawing said cam from said bearing, the spacing between the lines may be reduced.

The actuating means for the platen 126, the 15 paper feed cylinder 130 and its appurtenances, and the paper feed mechanism consists of a shaft 148 having an elongated operating lever 149. Said shaft 148 has two short arms 150, each of which is connected with a third arm 151 of the lever 20 carrying the platen. The shaft 148 carries a counterweight 152. The operating lever 149 extends to adjacent the front of the machine and has a handle grip 153.

The shaft 148 is positioned rearwardly of the 25 machine. There is one short arm 150 at each side of the machine, and there is one three armed lever 127—128—151 at each side of the machine so as to properly support both ends of the impression platen.

By the construction above described, a sort of 30 toggle lever connection is provided between the operating lever 149 and the platen bar 126, thus ensuring a desired high pressure relation between the platen and the types from which an impres- 35 sion is being made.

When the types are to be inked prior to the 40 making of the impression, an inking mechanism 154 and its actuating mechanism 155 is employed, but a detailed description of this mechanism is copending application above referred to.

Broadly, as hereinafter stated, this inking mechanism includes therein a vertically reciprocating frame carrying the inking mechanism proper, and an actuating mechanism operative thereon for imparting one complete reciprocating movement thereto with each actuation of the movable member of the printing couple and prior to the making of each impression, connections 45 between said actuating mechanism and the means for imparting relative movement to the members of the printing couple being provided, said connections including therein means whereby said inking mechanism is brought into and out of the 50 operative relation to the types during the movement of the platen toward said types.

Three pawls 136 are used to ensure accuracy in 55 the initial and full turning movement of the paper cylinder 130. Each pawl is provided with a heel 156 engageable by a stop 157 upon a slide 158 carried by the swing frame 135, so that all of these pawls may be made inoperative in relation to the ratchet wheel 134 when the cylinder 130 is turned while placing a sheet of paper upon 60 the cylinder. Set screws 159 are used to lock the slide in its inoperative position, the central screw 159 being used to actuate the slide 158.

In conjunction with the printing mechanism, it is desirable to use a locking and alining bar 65 operative upon the various type carrying members 33 closely adjacent the point of engagement of the platen 126 with the type.

In the form of the invention shown, I employ 70 forked brackets 160 toward opposite sides of the 75

machine, extending between which is an alining and locking bar 161 movable in the forked ends of the brackets 160 radially of the various type carrying members 33 and engageable with the space between the platens carrying the types. This bar 161 carries rods 162 mounted in lugs 163 upon the brackets 160. Said bar is acted upon by springs 164 acting between the bar and the lugs 163 to normally hold said bar out of engaging relation with the various type carrying members.

Carried by the opposite arms 127 are hooked spring members 165 which, with movement of the platen 126 toward the members 33, engage the bar 161 and force it into engagement with said members 33 against the tension of the springs 164. Upon the reverse movement of said platen, however, the hooked portion of said spring arms 165 imparts an initial movement to the alining and locking bar 161 out of engagement with the type carrying members 33, the arcuate path of the spring arms resulting in the automatic disengagement of the hooked portion thereof from said bar 161, so as to avoid the removal of the bar 25 from said brackets 160.

While means restraining outward movement of the bar 161 may be employed, this is not necessary if springs 164 of light tension be used.

After an impression of each line has been made, it is necessary to distribute the type preparatory to the setting of the succeeding line. The distributing mechanism shown in the accompanying drawings is adapted for use in a machine in which the type carrying members consist of discs having spaced peripheral platens which are set by a rotary movement of the discs.

While, during the setting of the discs, it is unnecessary to restore the setting mechanism to the same position each time a disc is set, it is essential, in distributing the types, that all of the discs be brought into a corresponding zero position preparatory to the turning of the first disc in setting a line of type, since the setting bar 36 must be engaged with the various discs, and to so engage this bar, the slots or keyways 34 in the various discs must be brought into alinement to permit movement of the bar 36.

In distributing the type, it is essential that each disc 33 receive movement complementing that which is received in setting the type thereon to restore that disc to its normal zero position. Since different discs are turned a different number of degrees in setting, it is obvious that in distributing the type different discs must receive a correspondingly different degree of movement to bring them to the zero position.

The distributing mechanism shown in the drawings is so constructed as to progressively pick up the different discs according to their setting, and by a single continuing movement to restore, with one revolution of this distributing mechanism, all of the discs to the desired zero position.

To secure this result, I provide each of the discs 65 with a long tooth 166 projecting beyond the type carrying platens. No printing characters are used adjacent this long tooth since the presence of this tooth closely adjacent the line of printing will interfere with the operation of the printing mechanism.

When a line of type is set up, these teeth 166 will be distributed, according to the characters appearing in the printing line, throughout the circumference of the group of discs, in the manner shown in Fig. 25 of the drawings.

The various teeth 166 are of a height to engage a stop bar 167 upon the completion of the operation of the distributing mechanism. This stop bar is mounted in brackets 168 having cam slots 169 therein, the stop bar 167 being provided with pins 170 moving in said slots.

Mounted adjacent one of the brackets 168 is a bell crank operating lever 171, the forked end of which engages a pin 172 carried by said stop bar 167. Adjacent one end of the bar 167 is an adjustable stop screw 173 by which the longitudinal movement of the bar may be limited independently of the slots 169. Under normal conditions the bar 167 is retracted in relation to the various type carrying members so as to be out of the path of movement of the high teeth 166, thus permitting a free turning movement of said members 33 when the distributing mechanism is set in the neutral position.

Extending from the header 91 to a disc 174 idly mounted on the shaft 32, is a bar 175 spaced from the discs 33 by blocks 176. Rotatably mounted on said bar 175 is a rod 177 carrying a distributing plate 178 having a toe portion 179 and an angularly projecting heel portion 180. This plate is of a length to co-operate with all type carrying discs 33.

Carried by said rod 177 is an actuating crank 181 carrying a spring lock member 182, the head of which is adapted to enter one of a sequence of openings 183, 184 and 185.

Carried by the frame of the machine adjacent the crank 181 is a pivotal dog 186, upon one side of which is a stop pin 187. This dog 186 is so positioned as to engage the free end of the crank 181. With clockwise movement of said crank, the dog 186 will move away from the stop pin 187, so as to have no operative effect upon the crank 181, but with contra-clockwise movement when restoring the distributing mechanism to its normal inoperative position, engagement of the crank 181 with said dog will impart limited movement to said crank to restore the plate 178 to a neutral position, or to a position where the spring lock 182 will be in the operative relation to the opening 183.

As will more fully appear hereinafter, when setting the distributing mechanism immediately prior to its operation, the plate 178 is rocked by means of the crank 181 to bring the heel 180 to a position, as shown in Fig. 25, where it will be in engaging relation with the teeth 166. A limited direct and return oscillation is then imparted to the bar 175 so as to bring all of the teeth 166 positioned adjacent and above the stop 167 into a position where they can be engaged by the toe 179 of said plate 178. In so positioning the plate 178, the spring lock is engaged with the opening 184. After such short reciprocation, the crank 181 is moved toward the axis of the shaft 32, past the opening 183, into engagement with the opening 185 so as to remove the heel 180 out of engaging relation with the high teeth 166 and bring the toe 179 into such relation. After the types have been distributed, it is necessary to bring both the heel 180 and the toe 179 out of engaging relation with the teeth 166, which is done by moving the crank 181 until the spring lock engages the opening 183. The function of the pivotal dog 186 is to automatically engage the spring lock 182 with the opening 183 with the final retardation of the bar 175 to its normal position, shown in Fig. 24.

The brackets 168 are engageable by the bar 75

175 to limit the movement of said bar to slightly less than 360° of arcuate movement.

I also preferably include in the machine a type cleaning mechanism which may be used from time to time during the operation of the machine to remove excess ink and fluff from the type members.

This type cleaning mechanism comprises a tank 188 for type cleaning fluid, having mounted thereon in a distributing roller 189 immersed in the fluid in the tank, and a felt cleaning roller 190 projecting beyond the open top of the tank in a position where it may be, by oscillation of the support for the tank, brought into or moved out of engaging relation with the types upon the discs 33. This tank is supported by arms 191 toward opposite ends of the machine, having a dovetail slide 192 permitting removal or partial removal of the tank for cleaning and re-filling purposes. The arms 191 are acted upon by springs 193 having a normal tendency to move the tank 188 in a manner to engage the cleaning roller 190 with the types.

Carried by the tank 188 is a spring arm 194, the turned end of which is engageable with a keeper member 195 restraining the action of the springs 193 and holding the roller 190 well away from the types.

Carried by the spring arm 194 are finger pieces 196 by which the said member 194 may be disengaged from the keeper member 195 and the movement of the tank by the springs 193, or against the tension of these springs, controlled.

The operation of the herein described printing machine is substantially as follows:—

In the operation of the machine, the various type carrying members 33, in succession from left to right, are actuated to set up a line of the desired length. The number of letters in different lines, as well as the number of words in the line, will vary, so that in justifying each line, the spacing between the words in different lines will vary. In setting up the types in a line, the succeeding discs are successively actuated, the setting mechanism is disconnected from the disc immediately after it has been properly set, and the disc is locked before the setting mechanism is disconnected therefrom.

Upon the completion of the setting of each word, the part of the word spacing and the line justifying mechanism mounted upon the disc carrying the last letter of the word is set, but is held inoperative until the completion of the setting of the whole line, whereupon all of the word spacing and line justifying mechanisms are simultaneously actuated to spread the discs between adjacent words.

Since the letter or printing character at the extreme right of the line must be brought into exact vertical alignment with the last letter or character of all other lines impressed upon a sheet, it is obvious that the operative effect of the word spacing and the line justifying mechanism must be controlled so as to secure a movement of the various discs in accordance with the number of words and number of printing characters in the line. The mechanisms used for so controlling the actuation of said word spacing and line justifying mechanism must be adjustable to secure this effect, although by a differential operation of the mechanisms carried by the various type carrying members a part of this variation in the number of letters or the number of word spaces may be distributed throughout the word spaces in the line.

During the actuation of the word spacing and line justifying mechanism, the mechanism operative in turning the various discs is inoperative as to all discs so turned, but each of these discs is locked against rotation.

When each line of type has been set, the words spaced and the line justified, an impression of that line of type is made upon a sheet of paper, or upon a stencil sheet. After the making of the impression it is necessary to restore all of the type carrying members to their normal neutral position to distribute the type preparatory to the setting of the next line of type. When so distributing the type, it is essential that the type setting mechanism be disconnected from all of the discs 33 which have been set, and that the locking mechanism be also made inoperative as to these discs so as to permit a free turning movement of the discs.

As each disc is actuated to set up a given type or printing character, an impression corresponding with the type or other character set up is made upon a proof sheet, conveniently accessible to the operator of the machine, so that prior to the making of an impression, proof may be read to detect any error in the set up. Proofing of the set up in this manner is of importance in the operation of the machine of the invention, since any error in the set up of any line would require a reprinting of an entire page.

In a machine embodying the invention, the procedure is unlike that of any printing method in which a page impression or galley proof can be made, since the type in each line, after making the impression, is distributed. Consequently, as stated, any correction must be made, and any error in the set up must be detected, before an impression is made.

The above is a general brief description of the operative effects secured by a machine embodying the invention.

I will now describe in detail the successive operations with relation to the various parts by which each operative effect is secured.

Prior to the first operation in setting up type by means of the discs 33, the parts will be in the position shown more particularly in Fig. 4 of the drawings, the type setting bar 36 occupying its extreme position at the left of said figure with the high part 37 of this bar seated in the keyways 34 of all of the discs 33 in the machine. The discs 33 are all in close abutting relation, one to the other. The lock bar 64 is disengaged from all of the discs 33, and the latch member 66 is engaged with the slot 67 in said bar 64, so that the type setting bar 36 is connected with the locking bar 64 in a manner to cause simultaneous movement of both of these bars as the setting of the several discs 33 progresses from left to right of the machine.

The spring plunger 47 acts upon the ratchet bar 46 in a manner to engage the teeth of this bar with the member 45 upon the sleeve 44.

The filler bars 83 are moved to the extreme left in the various keyways 35, so that the main shaft 32 presents a smooth continuous surface throughout, except adjacent the high part 37 of the setting bar 36.

With the various parts in the position described, there will be a line of blank platens along the printing line, or platens which have no printing characters thereon. If wide spacing between words is required, these non-printing platens may be used as quads following the last letter of a word, and the word spacing and line justify-

ing mechanism carried thereby may be set. This expedient, however, is resorted to only when the number of letters or other printing characters in a line, and the number of words, are so few as to require excessive spacing.

This positioning of the various discs results in the high teeth 166 of all of the discs 33 being in alinement adjacent, but out of engaging relation with, the stop bar 167.

10 The pawl rings 11 of the various discs 33, and the pawls 11 and 18 of each disc, will be in the position shown in full lines in Fig. 7.

The stop 94 is then set so as to be engaged by the stop rods 93 with the spreading of the discs, 15 so that the last printing character in a line of type will come to the extreme right of a column of the desired width. The setting of this stop will vary according to the number of letters and words in a line, the original setting being merely 20 an approximate setting.

The distributing bar 175 will be resting upon the top of the brackets 168 in which the stop bar 167 is mounted. The spring lock 182 will be engaged with the opening 183, so that both the 25 heel 180 and the toe 179 of the plate 178 will be out of the path of movement of the various high teeth 166.

If the first letter of a column is to be positioned at the extreme left of a line, as indicated in Figs. 30 15 and 16, the operator turns the shaft 32 by means of the hand wheel 39 until the character 40, corresponding with the letter to be set, is alined with the index finger 41. In so turning the shaft 32, all of the discs 33 will be turned, including the disc being set by this turning of the shaft. The sleeve 44 will receive no turning movement with the shaft.

When a letter has been properly set, the operator turns the shaft 59 in a clockwise direction, 40 Fig. 2, by means of its crank handle 60. This movement of the shaft 59 results in various operative effects. Through the crank pin 61 it will move the ratchet bar 46 toward the bank of discs 33 which, through the ratchet tooth member 45 will move the sleeve 44 along the shaft 32, thus moving the setting bar 36 a distance sufficient to disengage the high part 37 of this bar from the keyway 34 and move it into the recessed portion 69 of the disc being set. With 50 the movement of said sleeve 44, the alining and locking bar 64 will be advanced, in relation to the disc being set, to the same extent as the setting bar 36 is withdrawn from that disc. The locking and alining bar 64 enters between the platens about the periphery of the type carrying member or disc.

With this initial movement of the shaft 59, the high part 37 of the setting bar 36 is moved out of the keyway 34 in the disc, and simultaneously 60 with this release of the disc in relation to said setting bar, the locking and alining bar will engage the disc so as to hold it against further movement during the setting of the line of type.

With this initial movement of the shaft 59, the 65 hooked pawl 115 engages and turns the ratchet wheel 114 by the length of one tooth, and the star wheel 113 one-half the distance between the arms of this wheel. Since the crank handle 60 actuates the shaft 59 through the sleeve 118, having a lost motion connection between same and said shaft, said sleeve 118 will receive movement prior to the shaft and thus cause the cam 120 to actuate the lock member 43 in a manner to hold the setting wheel 39 against movement 70 by the engagement of the tooth of said locking

member with the teeth 42 about the edge of the said setting wheel. The partial turning of the star wheel 113 turns the ratchet wheel 112 and thus advances the proof tape 102-103 by the feeding rollers 106. This is accomplished by one 5 of the teeth of the star wheel 113, the following tooth of this wheel, by engagement with the cam 110, moving the proofing hammer 109 against the tension of its spring 111.

When turning the setting wheel 39, the printing character 100 corresponding with the character being set, will be brought opposite the opening 101 in the guide 99, or in operative relation to the proofing hammer 109. With the parts in this relation, the crank handle 60 is permitted a return oscillatory movement by the spring 119, during the final stages of which the shaft 59 will be turned to impart a return movement to the ratchet bar 46 without, however, any return movement of the sleeve 44, since the 20 ratchet bar 46 will be depressed during this return movement against the tension of the spring pressed plunger 47 in riding over the teeth of the ratchet tooth member 45.

The locking member 43 is used to prevent accidental turning of the setting wheel 39 since, while the type carrying member already set is locked against movement of the locking and alining bar 64, the shaft 32 and said wheel 39 carried thereby are not so locked.

If the type thus brought into the printing line is only one letter of a word and not the last letter thereof, the crank handle 60 is then again turned clockwise and the various parts above referred to again actuated in the manner described. 35

With the first actuation of the ratchet bar 46 and the setting bar 36, the setting bar is moved out of engaging relation with the discs 33 and into engaging relation with the pawl ring 11. With the second actuation of the ratchet bar 46 of each 40 cycle, the setting bar 36 is moved out of engaging relation with said pawl ring.

During this second movement of the crank handle 60, the arm of the star wheel 113 engaged with the cam arm 110 during the first movement 45 of the shaft 59, is moved out of such engagement and brought into the operative relation to the ratchet wheel 112 without, however, imparting any feeding movement to the proof tapes. With the freeing of the cam arm 110 from restraint 50 by the star wheel 113, the spring 111 imparts a rapid movement of the proofing hammer 109 toward the guide 99. This movement is sufficiently rapid to violently project or catapult the plunger 109a toward the tape 103, so as to secure a staccato blow ensuring a good clean imprint upon the tape or strip 103 by the carbon upon the strip or tape 102. 55

The soft resilient head 109b of the proofing hammer will, as a result of printing impact with 60 the types 100, cause a rebound of the plunger 109a to within the cylinder 109c.

During the second clockwise movement of the crank handle 60, the locking member 43 will again be engaged with the teeth 42, the lost motion connection between the sleeve 118 and the shaft 59 ensuring the locking of the setting wheel prior to the actuation of any of the other mechanisms receiving power from said crank handle 60. This second clockwise movement of the 70 crank handle 60 completes the cycle of operations when it is merely desired to set up a letter in a word, and the various parts, except as to the disc 33, actuated to set up a letter, have the same 75

operative relation to each other as prior to the actuation of that disc.

If the first letter to be set up is in a paragraph, it is obvious that there must be a plurality of complete cycles of operation of the crank handle 60 and the parts actuated thereby without turning of the setting wheel 39 or any of the discs 33. This will result in the presence of a number of non-printing platens in the printing line 10 corresponding with the quads or slugs used in hand setting type.

At this point it may be pointed out that the spring 121 will disengage the locking member 43 from the teeth 42 upon a contra-clockwise movement of the sleeve 118 by the spring 119.

The foregoing operations are repeated with each letter of a word, but are varied after the last letter of a word has been set, by the actuation of the machine to set the word spacing and 20 line justifying mechanism.

When the last letter of a word has been set and before the second actuation of the crank handle 60 in the cycle of setting that letter, the end of the high part 37 of the setting bar 36 will be in 25 engaging relation with the forward wall of the recess 76 in the pawl ring 71. To set the pawls 77 and 78, the shaft 32 is turned until the high part 37 of the setting bar engages the stop member 97 upon the disc 33. This is a short movement as indicated in dotted lines in Fig. 10.

During the movement of the shaft 32 and the setting bar 36 while the high part 37 of said bar is engaged with the wall of the recess 76, the pawl ring 71 will be moved in relation to the disc 33 carrying same. This movement is a combined 35 rotary and radial movement, the movement of the cam 73 in relation to the spring 74 and the action of the cam 72 upon the clip 70 associated therewith, controlling the movements of the ring and respectively permit and impart a radial component of movement thereon. This radial movement brings the pawls 77 and 78 into engagement with filler bars 83 carried by the shaft 32, as shown in dotted lines in Fig. 10.

The short turning movement of the ring brings the shoes 81 closely adjacent the cam surfaces 80 extending about the recess 69, these surfaces being formed upon the face of the discs proper 33. These shoes 81 being of a thickness to be normally within the plane of the face of the discs 33, the setting of the pawls 77 and 78 in the manner described will result in no movement of the discs longitudinally of the shaft 32.

When the pawl ring 71 has thus been actuated, the operator imparts the second clockwise movement of the crank handle 60, so as to move the setting bar out of engaging relation with the stop member 97 and with the pawl ring 71. The engagement of the pawls 77 and 78 with the filler bars 83 separates these pawls and tensions the spring 79. There is no flexure of the spring arms 82 during the setting of the pawl ring.

The setting of letters in succeeding words, the proofing of each letter as it is set and the actuation of the pawl rings 71 upon the disc carrying the last letter of each word is repeated until a line has been completely set up.

In the machine herein described as actually constructed, there are six type carrying members 33 to the inch, and sixty such members are used in the machine, so a line approximately eleven inches long may be set up, the extra inch representing word spacing and line justifying tolerance.

In Figs. 15 and 16, the length of the length of

the line is illustrated as being nine inches, in the actual machine and not in the drawings.

After a line has been set up, the operator draws the tapes 102 and 103 through the guide 99 and tears off a length of the tape 103, so that he can proof the line and count the number of letters and words in the line. In the line shown set up in said Figs. 15 and 16, there are forty-seven printing characters, including a period at the end of the line, and nine words, requiring eight spaces 10 between words.

It will be noted, by reference to Fig. 15, that all of the discs 33 are still in close abutting relation, one to the other, while in Fig. 16, the various words are spaced apart a distance slightly 15 less than the thickness of each disc 33. With this condition, the discs must be separated or spread to an extent to bring the forty-seventh disc from the left into the position of the fifty-fourth disc, as shown in Fig. 15. Consequently, 20 the stop member 94 must be set so as to permit a movement of the header 92 to an extent to bring the forty-seventh disc into the position above indicated.

If the number of words in a line were less, or 25 the number of letters less, greater movement would be required of the header 92 and the stop 94 must be adjusted accordingly. If the number of words were more, or the number of letters were more, less movement would be required of 30 the header 92 and the stop 94 would have to be set closer to said header. In some lines, where the number of words and letters is materially less than the space required in setting a nine 35 inch line, it may be necessary, after the last letter of a word has been set, to actuate the crank handle 60 once without any movement of the shaft 32, to have a spacing quad positioned between succeeding words, and then to have this handle actuated a second time to set the pawl ring 71 upon the disc having no printing character in the printing line.

When the stop 94 has been set, the shaft 88 is turned by its hand crank 90 so as to draw the head 84 and the various filler bars 83 to the 45 right, Fig. 4, to an extent to permit the springs 79 to move the pawls 77 and 78 into the keyways 35 exposed by the movement of these filler bars.

The shaft 32 is then turned, movement of this shaft being transmitted to the various pawl rings 71 which have been set in the manner heretofore described. With the turning of these rings, the spring arms 82 are moved circumferentially of the shaft 32, and the bearing shoes 81 move along the cams 80 and axially of said shaft, during which movement they engage the adjacent discs 33 to the right, sliding these discs along the shaft until further turning movement of the shaft and of the pawl rings is prevented by engagement of the stop rods 93 with the stop 94.

With this mode of operation the total amount of movement of the header 92 is divided substantially equally between the shoes upon each pawl ring which is actuated. For example, in the example illustrated in Figs. 15 and 16, the 65 amount of movement of the header 92 is equal to the thickness of seven discs. Consequently, the spacing between the different words in the set line will, in each instance, amount to seven-eighths of the thickness of the disc. If only 70 forty-six letters had been used, the spaces between the words would have been equal to the width of a disc, while of forty-eight letters had been used, each space would have been equal to three-fourths of the width of a disc. If the same 75

number of words are in the line but only forty-two letters are used, it would have been necessary to follow each word, during the setting of the line of types, with a disc having a non-printing platen with its pawl ring set in the manner described, so that with the final actuation of these pawl rings, the spaces between the different words would be equal to the full width of a disc, plus one-half that width.

10 During this movement of the groups of discs, all of the discs are limited to movement longitudinally of the shaft 32 by the alining and locking bar 64, so that there will be no disturbance of the types in the printing line.

15 Prior to the making of an impression upon the line of type so set, word spaced and justified, a sheet of paper or stencil sheet is passed under one of the paper clips 132. The paper feed pawls 136 are then disengaged from the ratchet wheel 134 by movement of the slide 158 to engage the various stops 157 with the heels 156 of the various pawls. The paper roller or cylinder may then be turned freely by hand, the sheet being passed across the bar 126 forming the printing platen, 20 and the bottom of the sheet engaged with the other clamp bar 131. The slide 158 is then returned to its normal inoperative position in relation to the feed pawls 136.

The operator then grasps the operating lever 149 by the handle 153 and rocks the shaft 148 in a clockwise direction from the right of Fig. 1. This movement of the shaft 148 through the short arms 150 rocks the three armed lever 127-128-151 about the shaft 129, thus, by a toggle lever action, forcing the platen bar 126 toward the various type carrying members 33 so as to make an impression upon the paper passing over this platen.

The movement of the shaft 129, when an inked impression is to be made will, through the mechanism 155, bring the inking mechanism 154 into operative relation to the type upon the printing line, said inking mechanism having a direct and return reciprocation during the early stages in the movement of the three armed lever, and being actuated to ensure a proper application and distribution of ink during this reciprocation.

The detailed construction and mode of operation of this inking mechanism is set forth in my co-pending application above referred to, and need not be repeated.

With the turning movement of the shaft 129, the arm 137 turns with the shaft and through the spring 138 rocks the swing frame 139, the adjustable screw bearing upon the shaft 129 controlling the movement of this frame and permitting nicety in the adjustment of the frame to ensure a proper feeding movement of the various pawls 136.

60 After the impression is made, the operating lever 149 is drawn toward the operator, thus imparting a return rocking movement to the three armed lever and carrying the swing frame 135 with it. During this return movement, the roller 141 upon the arm 140 engages the cam 142 and so rocks the frame about the shaft 133 as to turn the paper roller or cylinder a distance to secure the desired spacing between succeeding line impressions. To reduce the line spacing, 65 the cam 142 is moved to the right, Fig. 3, by the lead screw 144, while to increase the line spacing, said cam is moved to the left in said figure.

As the impression platen bar 126 moves toward the type carrying members or discs 33, the auxiliary locking and alining bar 161 is engaged by

the spring hooks 165 and forced, against the tension of the springs 164, into spaces between platens upon the various discs 33, thus supplementing the action of the bar 64 in holding these discs against possible slight movement during the making of an impression.

As the platen bar and said spring hooks 165 move away from the discs 33, the spring hooks 165 will impart a starting impulse to the locking and alining bar 161, so as to ensure the disengagement of this bar from the various discs 33 following the making of the impression.

The upward arcuate path of the hooks 165 causes them to automatically clear the bar 161 following the initial return movement of said 15 spring hooks.

After an impression has thus been made of a single line of type, it is essential to re-distribute the types preparatory to the setting of the next line.

Following the making of the impression, the relation of parts will be as follows: The auxiliary locking and alining bar 161 will be disengaged from all of the discs 33. The high part 37 of the setting bar 36 will be disengaged from all of the 25 discs used in setting up the line of type from which the impression was made. The lock bar 64 will be engaged with all of the discs from which the impression was made. The various 30 filler bars will be moved well to the right in Fig. 1 out of the grooves 35 adjacent the various discs from which an impression has been made. The high teeth 166 of the several discs will be spaced at 35 different intervals about the bank of discs, as indicated in Figs. 25 and 26, according to the letters upon the several discs appearing in the printing line. The stop bar 167 will be moved out of the path of the various high teeth 166. The distributing plate 178 will be set in a position with the heel portion 180 and the toe portion 179 out of the 40 plane of movement of said high teeth.

Before restoring the various discs 33 to their neutral position, the shaft 32 is given a contra-clockwise movement, see Fig. 13, by the hand wheel 39. This movement of the shaft through the pawl 78, imparts a contra-clockwise movement to the pawl rings 71 and moves the various bearing shoes 81 downwardly along the cam surfaces 80. During this movement, the spring 74 will exert a pressure tending to impart radial movement to its pawl ring as it engages the cam 73 and as the cam 72 comes into the operative relation with its associated clip 70. The spring 74, as the cam 73 passes thereunder, imparts the desired radial thrust to the ring to disengage the pawls 71 and 78 from the keyways 34, and completes the turning movement of the pawl ring 71 to restore said pawl ring to its normal position, as shown in Fig. 7, with the pawls 71 and 78 out of contact with the periphery of the shaft 32.

The stop 75 limits turning movement of the pawl ring in one direction by engagement with one of the clips 70, and, if necessary, also in the opposite direction by engagement with another of said clips 70.

The spring arms 82 act to restore the bearing shoes 81 to their position within the plane of the surface of the discs 33.

The lock bar 64 is then disconnected from the sleeve 44 by raising the latch 66, and this bar is moved by means of the finger grip 68 out of engaging relation with all of the discs 33. Under the above condition, each of the discs 33 is free to turn upon the shaft 32.

The distributing plate 178 is then turned by the 75

actuating crank 181 in a manner to disengage the spring lock member 182 from the opening 183 and engage it with the opening 184. This will bring the lock plate in the position shown in Fig. 5 with the heel portion 180 closely adjacent the stop bar 167 and in a position where, with turning movement of the header 91 and the disc 174, by hand, in a clockwise direction, any high teeth 166 adjacent and above the stop bar 167 10 will be successively engaged by said heel portion so as to move the discs carrying same with said header and said disc.

This movement of the distributing plate, when set as described, is limited to a distance slightly 15 greater than the total width of the plate 178. The header 91 and the disc 174 then receive a reverse movement until the bar 175 engages the brackets 168. The distributing plate is then turned in the opposite direction so as to engage 20 the lock member 182 with the opening 185 and bring the toe portion 179 of said plate to a position where, with clockwise movement of the plate with the header 91 and the disc 174, it will engage any of the high teeth in its path of movement.

25 The stop bar meanwhile has been advanced to occupy a position in the path of the high teeth 166, so that with a substantially full rotation of the header 91 and the disc 174, the high teeth upon all of the discs, irrespective of their position 30 during the printing operation, will be brought into alignment adjacent and in abutting relation to said stop bar.

At one point of this full rotation of the distributing plate 178, the arm 181 will engage the 35 pivotal dog 186 which will move from impact of said arm. After all of the discs have been re-set to re-distribute the type in the manner above described, a return full revolution is imparted to the header 91 and the disc 174 to restore the bar 175 to its normal position engaging the top 40 of the brackets 168.

During this return movement, the actuating crank 181 will again engage the pivotal dog 186, but the stop pin 187 prevents turning of this dog 45 by said lever, so that the lever will be shifted in a manner to disengage the lock member 182 from the opening 185 and engage it with the opening 183 to restore the distributing plate 178 to its neutral inoperative position.

When the discs have been so actuated to distribute the type, the keyways or slots 34 in all of the discs will be in alignment.

The shaft 50 is then turned to disengage the ratchet bar 46 from the ratchet tooth member 45, the eccentric pin 49 of this shaft constituting 55 means for disengaging said ratchet bar from said ratchet tooth.

The sheave 54 is then turned in a contra-clockwise direction to move the sleeve 44 along the shaft 32, to the left, by means of the cord 51. This movement of the sleeve 44 draws the setting bar 36 so that the high part 37 thereof will pass through the various aligned keyways or slots 34 in the discs 33.

60 As the sleeve 44 reaches the limit of its return movement, the latch member 66 will automatically enter the keeper slot 67 in the alining and locking bar 64.

The shaft 50 is then actuated to permit the 70 spring plunger 47 to engage the ratchet bar 46 with the ratchet tooth 45.

The crank 90 is then actuated in a contra-clockwise direction to move the various filler bars 83 to a position where they will occupy the various slots 35 about the shaft 32. In the mean-

while, however, before or after the operations above described, the header 92 is moved to the left, Fig. 4, by hand, to space the ends of the stop rods 93 from the stop member 94 and to restore the various discs 33 to their close abutting relation.

The stop bar 167 is then moved out of engaging relation with the various high teeth 166.

The stop bar 167 is moved into and out of its operative relation to the teeth 166 by the bell 10 crank operating lever 171 in the manner heretofore described.

The various parts of the machine are then in a position preparatory to the setting of the next line of type.

It is desirable that the type members upon the various discs 33 shall be kept clean in order that good sharp impressions may be made of all lines upon a sheet. Consequently, from time to time, the spring arm 194 is actuated to disengage this arm from the keeper member 195 so as to permit the spring 193 to rock the tank 188 in a manner to engage the soft roller 190 with the various printing characters upon the discs 33.

The shaft 32 and all of the discs may then be 25 turned freely so as to bring each of the types into operative relation to the cleaning roller.

The setting bar 36 prevents movement of the discs during the cleaning operation.

The spring 193 holds the roller 190 in yielding 30 engagement with the type members, so that if the high teeth 166 engage this roller, the only effect would be to move the roller away from the discs during such engagement, the roller immediately thereafter re-engaging the discs.

The herein described machine is not intended for rapid operation, but with acquired skill by an operator, the machine may be accurately operated at fairly high speeds, and accuracy is essential.

In the operation of the machine, no time is lost in conforming the set type to a corrected proof, and justifying a line requires but one rapid operation.

The various controls of the machine are conveniently accessible to the operator, and while the shaft 32 and its various discs 33 have considerable weight, this weight is so distributed as to permit ease in the operation of the discs when setting up a line of type.

It is not my intention to limit the invention to the precise details of construction shown in the accompanying drawings, it being obvious that the same mode of operation in the machine may be secured by means of mechanisms varying widely in their detailed structural characteristics.

I believe it to be broadly new to provide a printing machine in which one of the members of the printing couple embodies therein, and has associated therewith, a type setting mechanism by which a single line of type may be set up, and the members of the printing couple may be so actuated as to make an impression from each line of type as it is set up and prior to the distribution of the type preparatory to the setting of a succeeding line of type.

I also believe it to be broadly new to provide, in conjunction with the member of the printing couple embodying the type members, means whereby the type carrying members are provided with a word spacing and line justifying mechanism by which the type carrying members may be so moved as to space words in a line and at the same time justify the line of type.

The provision in a printing machine in which one line of type is set at a time and an impression then made of this line of type, of a proofing mechanism by which an impression is made indicating each letter as it is set up, I believe to be broadly new.

I also believe it to broadly new to provide in a machine which is capable of being so operated as to set up one line of type at a time and to make an impression of that line of type, a mechanism by which, following the making of the impression, the various type carrying members are so actuated as to distribute the type preparatory to the setting up of a succeeding line of type.

15 While the foregoing characteristics, which I consider broadly new, are of major importance in a machine embodying the invention, the machine possesses other novel characteristics which, while of secondary importance, are, nevertheless, 20 I believe, also broadly new.

Having described the invention, what I claim as new and desired to have protected by Letters Patent, is:—

1. A printing machine embodying therein a printing couple, one of the members of which has a type setting mechanism comprising a single shaft having mounted thereon a plurality of co-axial independently and differentially rotatable type carrying members, actuating means carried by and rotatable with said shaft and common to all of said members and progressively operative thereon, and means for holding each member stationary after it has been actuated, whereby a single line of type may be set at a time, and the other member of which has an impression platen, means whereby the members of said couple may be given relative movement to make an impression from each line of type after it has been set up, and means whereby the type in said line of type may be distributed preparatory to the setting of a succeeding line of type.

2. A printing machine embodying therein a printing couple, one of the members of which has a type setting mechanism comprising a single shaft having mounted thereon a plurality of co-axial independently and differentially rotatable type carrying members, actuating means carried by and rotatable with said shaft and common to all of said members and progressively operative thereon, and means for holding each member stationary after it has been actuated, whereby a single line of type may be set at a time, and the other member of which has an impression platen, a word spacing and line justifying mechanism operative upon the type in said line of type, means whereby the members of said couple may be given relative movement to make an impression from each line of type after it has been set up and said word spacing and line justifying mechanism has been actuated, and means whereby the type in said line of type may be distributed preparatory to the setting of a succeeding line of type.

3. A printing machine embodying therein a printing couple, one of the members of which has a type setting mechanism whereby a single line of type may be set at a time, and the other member of which has an impression platen, a proofing mechanism, means actuating said proofing mechanism after each type in said line has been set up, means whereby the members of said couple may be given relative movement to make an impression from each line of type after it has been set up, and means whereby the type in

said line of type may be distributed preparatory to the setting of a succeeding line of type.

4. A printing machine embodying therein a printing couple, one of the members of which has a type setting mechanism whereby a single line of type may be set at a time, and the other member of which has an impression platen, a proofing mechanism, means actuating said proofing mechanism after each type in said line has been set up, a word spacing and line justifying mechanism operative upon the type in said line of type, means whereby the members of said couple may be given relative movement to make an impression from each line of type after it has been set up and said word spacing and line justifying mechanism has been actuated, and means whereby the type in said line of type may be distributed preparatory to the setting of a succeeding line of type.

5. A printing machine embodying therein a printing couple, one of the members of which comprises a single rotatable shaft, a plurality of co-axial type carrying discs idly mounted upon said shaft, means for turning said shaft, setting means carried by and movable with said shaft engageable with said discs respectively, means whereby said setting means is disengaged from each disc after it has been set, and means engageable with each disc after it has been set to hold it in the set position, whereby said discs may be differentially and successively turned to set up a line of type, and the other member of which has an impression platen, actuating means whereby said setting means may be disengaged from each disc after it has been set, means whereby the members of said couple may be given relative movement to make an impression from each line of type after it has been set up, and means, independent of said setting means and operative upon all discs which have been set, whereby said type carrying discs may be actuated to distribute the type in said line of type preparatory to the setting of a succeeding line of type.

6. A printing machine embodying therein a printing couple, one of the members of which comprise a rotatable shaft, a plurality of type carrying discs idly mounted upon said shaft, means for turning said shaft, and setting means carried by said shaft engageable with said discs respectively, whereby said discs may be differentially and successively turned to set up a line of type, and the other member of which has an impression platen, actuating means whereby said setting means may be disengaged from each disc after it has been set, an alining and locking bar, means whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

7. A printing machine embodying therein a printing couple, one of the members of which comprises a rotatable shaft, a hand wheel carried thereby, a plurality of type carrying discs idly mounted upon said shaft each having a keyway therethrough, and a setting bar having a high part engageable with the keyways in the several discs, and a low part substantially flush with the circumference of said shaft, said bar being slidably mounted upon said shaft, whereby said discs may be differentially and successively turned to

set up a line of type, and the other member of which has an impression platen, a locking and alining bar normally disengaged from, but engageable with, the several discs, connections between said setting bar and said alining and locking bar, actuating means whereby said bars are simultaneously advanced along said shaft to disengage said setting bar from, and engage said alining and locking bar with, each disc as it is set, means whereby the members of said couple may be given relative movement to make an impression from each line of type after it has been set up, and means whereby said type carrying discs may be actuated to distribute the type in said line of type preparatory to the setting of a succeeding line of type.

8. A printing machine embodying therein a printing couple, one of the members of which comprises a rotatable shaft, a plurality of type carrying discs idly mounted upon said shaft, means for turning said shaft, word spacing and line justifying mechanisms carried by each disc in operative relation to the adjacent disc, means whereby said mechanisms may be selectively set, and setting means carried by said shaft engageable with said discs respectively and with selected word spacing and line justifying mechanisms, whereby said discs may be differentially and successively turned to set up a line of type and any said mechanisms may be set after the setting of a disc, means whereby upon the completion of the setting of a line of type all of said word spacing and line justifying mechanisms which have been set may be engaged with said shaft and actuated thereby, and the other member of which has an impression platen, actuating means whereby said setting means may be disengaged from each disc and its word spacing and line justifying mechanism after it has been set, an alining and locking bar, means whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

9. A printing machine embodying therein a printing couple, one of the members of which comprises a rotatable shaft, a plurality of type carrying discs idly mounted upon said shaft, means for turning said shaft, word spacing and line justifying mechanisms carried by each disc in operative relation to the adjacent disc, means whereby said mechanisms may be selectively set, and setting means carried by said shaft engageable with said discs respectively and with selected word spacing and line justifying mechanisms, whereby said discs may be differentially and successively turned to set up a line of type and any said mechanisms may be set after the setting of a disc, means whereby upon the completion of the setting of a line of type all of said word spacing and line justifying mechanisms which have been set may be engaged with said shaft and actuated thereby, and the other member of which has an impression platen, actuating means whereby said setting means may be disengaged from each disc and its word spacing and line justifying mechanism after it has been set, means limiting the operative effect upon said discs of said word spacing and line justifying mechanisms, an alining and locking bar, means whereby said bar may

be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

10. A printing machine embodying therein a printing couple, one of the members of which comprises a rotatable shaft, a plurality of type carrying discs idly mounted upon said shaft, means for turning said shaft, word spacing and line justifying mechanisms carried by each disc in operative relation to the adjacent disc, means whereby said mechanisms may be selectively set, and setting means carried by said shaft engageable with said discs respectively and with selected word spacing and line justifying mechanisms, whereby said discs may be differentially and successively turned to set up a line of type and any said mechanisms may be set after the setting of a disc, means whereby upon the completion of the setting of a line of type all of said word spacing and line justifying mechanisms which have been set may be engaged with said shaft and actuated thereby, and the other member of which has an impression platen, actuating means whereby said setting means may be disengaged from each disc and its word spacing and line justifying mechanism after it has been set, an adjustable stop member, means engaged by and movable with said discs and engageable with said stop member to limit the operative effect of said word spacing and line justifying mechanisms upon said discs, an alining and locking bar, means whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

11. A printing machine embodying therein a printing couple, one of the members of which comprises a rotatable shaft having a plurality of longitudinally extending peripheral slots, filler bars movably mounted in said slots, a plurality of type carrying discs idly mounted upon said shaft, each of said discs having a recess in and cam surfaces on one side thereof, means for turning said shaft, a pawl ring mounted for rotation and radial movement in the recess of each disc, a plurality of pawls carried by said ring, shoes yieldably supported by said ring in operative relation to said cam surfaces, a spring acting on said pawls to move them toward said shaft, and setting means carried by said shaft engageable with said discs and said rings respectively, whereby said discs may be differentially and successively turned to set up a line of type, and said pawls may be set in operative relation to said shaft, means whereby said filler bars may be withdrawn from said slots to permit engagement of said pawls therewith, whereby with turning movement of said shaft the rings carrying all pawls engaging said shaft will be turned to cause the actuation of said shoes in separating adjacent discs, and the other member of which has an impression platen, actuating means whereby said setting means may be disengaged from each disc after it has been set, an alining and locking bar, means

whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

12. A printing machine embodying therein a printing couple, one of the members of which comprises a rotatable shaft having a plurality of longitudinally extending peripheral slots, filler bars movably mounted in said slots, a plurality of type carrying discs idly mounted upon said shaft, each of said discs having a recess in and cam surfaces on one side thereof, means for turning said shaft, a plurality of guide clips in said recess, a pawl ring engageable by said clips, cams upon opposite diameters of said ring, one of which is engageable with a guide clip, a spring acting upon the other of said cams, said ring having a shouldered recess therein, a plurality of oppositely set pawls carried by said ring, shoes yieldably supported by said ring in operative relation to said cam surfaces, a spring acting on said pawls to move them toward said shaft, and setting means carried by said shaft engageable with said discs and said rings respectively, whereby said discs may be differentially and successively turned to set up a line of type, and said pawls may be set in operative relation to said shaft, means whereby said filler bars may be withdrawn from said slots to permit engagement of said pawls therewith, whereby with turning movement of said shaft the rings carrying all pawls engaging said shaft will be turned to cause the actuation of said shoes in separating adjacent discs, and the other member of which has an impression platen, actuating means whereby said setting means may be disengaged from each disc after it has been set, an alining and locking bar, means whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

13. A printing machine embodying therein a printing couple, one of the members of which comprises a rotatable shaft having a plurality of longitudinally extending peripheral slots, filler bars movably mounted in said slots, a plurality of type carrying discs idly mounted upon said shafts, each of said discs having a recess in and cam surfaces on one side thereof, means for turning said shaft, a plurality of guide clips in said recess, a pawl ring engageable by said clips, cams upon opposite diameters of said ring, one of which is engageable with a guide clip, a spring acting upon the other of said cams, said ring having a shouldered recess therein, a plurality of oppositely set pawls carried by said ring, shoes yieldably supported by said ring in operative relation to said cam surfaces, a spring acting on said pawls to move them toward said shaft, and setting means carried by said shaft engageable with said discs and said rings respectively, whereby said discs may be differentially and successively turned to set up a line of type, and said pawls may be set in operative relation to said shaft, means limiting the movement of the ring by said setting

means when setting said pawls, means whereby said filler bars may be withdrawn from said slots to permit engagement of said pawls therewith, whereby with turning movement of said shaft the rings carrying all pawls engaging said shaft will be turned to cause the actuation of said shoes in separating adjacent discs, and the other member of which has an impression platen, actuating means whereby said setting means may be disengaged from each disc after it has been set, an alining and locking bar, means whereby said bar may be engaged with said discs simultaneously with the disengagement of said setting means therefrom, means whereby the members of said couple may be given relative movement to make an impression from each line of type after it has been set up, and means whereby said type carrying discs may be actuated to distribute the type in said line of type preparatory to the setting of a succeeding line of type.

14. A printing machine embodying therein a printing couple, one of the members of which has a type setting mechanism comprising a single shaft having mounted thereon a plurality of co-axial independently and differentially rotatable type carrying members, actuating means carried by and rotatable with said shaft and common to all of said members and progressively operative thereon, and means for holding each member stationary after it has been actuated, whereby a single line of type may be set at a time, and the other member of which has an impression platen, a paper feed cylinder adjacent said platen, means actuating said paper feed cylinder following the making of each impression to space the lines of succeeding impressions, means whereby the members of said couple may be given relative movement to make an impression from each line of type after it has been set up, and means, independent of said means for turning said type carrying members and operative upon all of said members, whereby the type in said line of type may be distributed preparatory to the setting of a succeeding line of type.

15. A printing machine embodying therein a printing couple, one of the members of which has a type setting mechanism whereby a single line of type may be set at a time, and the other member of which embodies therein three armed levers, one arm of each of which is pivoted adjacent the bed of the machine, a platen bar carried by other arms of said levers, a crank shaft, a pivotal connection between the cranks of said shaft and other arms of said levers, an actuating lever for said shaft whereby said platen may be actuated to make an impression from each line of type after it has been set up, a paper feed cylinder mounted in said lever adjacent said platen, means actuating said paper feed cylinder following the making of each impression to space the lines of succeeding impressions, and means whereby the type in said line of type may be distributed preparatory to the setting of a succeeding line of type.

16. A printing machine embodying therein a printing couple, one of the members of which has a type setting mechanism whereby a single line of type may be set at a time, and the other member of which embodies therein three armed levers, one arm of each of which is pivoted adjacent the bed of the machine, a platen bar carried by other arms of said levers, a crank shaft, a pivotal connection between the cranks of said shaft and other arms of said levers, an actuating lever for

- 5 said shaft whereby said platen may be actuated to make an impression from each line of type after it has been set up, a paper feed cylinder mounted in said lever adjacent said platen, a swing frame coaxial with said feed cylinder, a ratchet wheel carried by said cylinder, a pawl carried by said swing frame and co-operating with said ratchet wheel, a cam operative to oscillate said frame and said pawl upon the return 10 movement of said three armed levers following the making of each impression, and means whereby the type in said line of type may be distributed preparatory to the setting of a succeeding line of type.
- 15 17. A printing machine embodying therein a printing couple, one of the members of which has a type setting mechanism whereby a single line of type may be set at a time, and the other member of which embodies therein three armed levers, one arm of each of which is pivoted adjacent the bed of the machine, a platen bar carried by other arms of said levers, a crank shaft, a pivotal connection between the cranks of said shaft and other arms of said levers, an actuating lever 20 for said shaft whereby said platen may be actuated to make an impression from each line of type after it has been set up, a paper feed cylinder mounted in said lever adjacent said platen, a swing frame coaxial with said feed cylinder, a ratchet wheel carried by said cylinder, a pawl carried by said swing frame and co-operating with said ratchet wheel, a cam operative to oscillate said frame and said pawl upon the return 25 movement of said three armed levers following the making of each impression, means whereby said cam may be adjusted toward and from said frame to vary the line spacing between succeeding impressions, and means whereby the type in said line of type may be distributed preparatory to the setting of a succeeding line of type.
- 30 18. A printing machine embodying therein a printing couple, one of the members of which has a type setting mechanism whereby a single line of type may be set at a time, and the other member of which embodies therein three armed levers, one arm of each of which is pivoted adjacent the bed of the machine, a platen bar carried by other arms of said levers, a crank shaft, a pivotal connection between the cranks of said 35 shaft and other arms of said levers, an actuating lever for said shaft whereby said platen may be actuated to make an impression from each line of type after it has been set up, a paper feed cylinder mounted in said lever adjacent said platen, a swing frame coaxial with said feed cylinder, a ratchet wheel carried by said cylinder, a pawl carried by said swing frame and co-operating with said ratchet wheel, a rod carried by and movable with said three armed levers, a spring 40 connecting said rod with said frame whereby said frame receives oscillatory movement with said levers, a cam operative to oscillate said frame and said pawl upon the return movement of said three armed levers following the making of each impression, and means whereby the type in said line of type may be distributed preparatory to the setting of a succeeding line of type.
- 45 19. A printing machine embodying therein a printing couple, one of the members of which has a type setting mechanism whereby a single line of type may be set at a time, and the other member of which has an impression platen, a paper feed cylinder adjacent said platen, means actuating said paper feed cylinder following the 50 making of each impression to space the lines of

5 succeeding impressions, means whereby the members of said couple may be given relative movement to make an impression from each line of type after it has been set up, an inking mechanism vertically movable between the member having the type setting mechanism and said platen, an actuating mechanism therefor, connections between said actuating mechanism and the means imparting relative movement to the members of said printing couple, including there- 10 in means whereby said inking mechanism is brought into and out of the operative relation to the types during the movement of the platen toward said types, and means whereby the type in said line of type may be distributed prepara- 15 tory to the setting of a succeeding line of type.

20 21. A printing machine embodying therein a printing couple, one of the members of which comprises a rotatable shaft, means whereby said shaft may be turned, a plurality of type carrying 20 discs idly mounted upon said shaft each having a keyway therethrough, and a setting bar having a high part engageable with the keyways in the several discs, and a low part substantially flush with the circumference of said shaft, said bar being slidably mounted upon said shaft, whereby said discs may be differentially and successively turned to set up a line of type, and the other member of which has an impression platen, a locking and alining bar normally disengaged from, but engageable with, the several discs, a sleeve 25 slidably mounted upon said shaft, connections between said sleeve and said setting and said locking and alining bars respectively, a ratchet bar mounted adjacent said sleeve, a pawl carried by said sleeve co-operating therewith, a shaft carrying an eccentric pin engageable with said ratchet bar to impart reciprocatory movement thereto, a crank operative upon said shaft whereby said bars are simultaneously advanced along said shaft 30 to disengage said setting bar from, and engage said alining and locking bar with, each disc as it is set, means whereby the members of said couple may be given relative movement to make an impression from each line of type after it has been 35 set up, and means whereby said type carrying discs may be actuated to distribute the type in said line of type preparatory to the setting of a succeeding line of type.

40 22. A printing machine embodying therein a printing couple, one of the members of which comprises a rotatable shaft, means whereby said shaft may be turned, a plurality of type carrying 40 discs idly mounted upon said shaft each having a keyway therethrough, word spacing and line 45 justifying mechanisms carried by each disc in operative relation to the adjacent disc, and a setting bar having a high part engageable with the keyways in the several discs and with selected word spacing and line justifying mechanisms, and a low part substantially flush with the circumference of said shaft, said bar being slidably mounted upon said shaft, whereby said discs may be differentially and successively turned to set up a line of type and any said mechanism may be set after the setting of a disc, and the other member of which has an impression platen, a locking and alining bar normally disengaged from, but engageable with, the several discs, a sleeve 50 slidably mounted upon said shaft, connections between said sleeve and said setting and said locking and alining bars respectively, a ratchet bar mounted adjacent said sleeve, a pawl carried by said sleeve co-operating therewith, a shaft carrying 55 an eccentric pin engageable with said ratchet 60 bar to impart reciprocatory movement thereto, a crank operative upon said shaft whereby said bars are simultaneously advanced along said shaft to disengage said setting bar from, and engage said alining and locking bar with, each disc as it is set, means whereby the members of said couple may be given relative movement to make an impression from each line of type after it has been 65 set up, and means whereby said type carrying discs may be actuated to distribute the type in said line of type preparatory to the setting of a succeeding line of type.

70 75 75

bar to impart reciprocatory movement thereto, a crank operative upon said shaft whereby with one actuation of said crank, the high part of said setting bar will be disengaged from a disc and brought into the operative relation to the word spacing and line justifying mechanisms carried by that disc, and said alining and locking bar will be engaged with said disc, and upon the next actuation of said crank said setting bar will be moved out of the operative relation with said mechanism, means whereby the members of said couple may be given relative movement to make an impression from each line of type after it has been set up, and means whereby said type carrying discs may be actuated to distribute the type in said line of type preparatory to the setting of a succeeding line of type.

22. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, and the other member of which has an impression platen, a proof tape guide adjacent the periphery of said hand wheel, tape actuating means, a spring pressed lever pivotally mounted adjacent said guide, a proofing hammer carried by said lever, actuating means whereby said setting means may be disengaged from each disc after it has been set, and said spring pressed lever and said proofing hammer are actuated to make a proof of the letter set prior to the operation of said actuating means, means whereby each disc after it has been set is locked against movement, means whereby the members of said couple may be given relative movement to make an impression from each line of type after it has been set up, and means whereby said type carrying discs may be actuated to distribute the type in said line of type preparatory to the setting of a succeeding line of type.

23. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, and the other member of which has an impression platen, a proof tape guide adjacent the periphery of said hand wheel, a shaft carrying feed rollers engageable with said tape, a ratchet wheel carried by said shaft, a star wheel co-operating with said ratchet wheel, a second ratchet wheel acting upon said star wheel, a bell crank lever, a spring acting thereon, a proofing hammer carried by one arm of said lever, a cam carried by said lever in engaging relation with said star wheel, actuating means for said setting means including therein means engaging the ratchet wheel acting upon said star wheel, means whereby each disc after it has been set is locked against movement, means whereby the members of said couple may be given relative movement to make an impression from each line of type after it has been set up, and means whereby said type carrying discs may be actuated to distribute the type in said line of type preparatory to the setting of a succeeding line of type.

24. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, and the other member of which has an impression platen, a proof tape guide adjacent the periphery of said hand wheel, a shaft carrying feed rollers engageable with said tape, a ratchet wheel carried by said shaft, a star wheel co-operating with said ratchet wheel, a second ratchet wheel acting upon said star wheel, a bell crank lever, a spring acting thereon, a proofing hammer carried by one arm of said lever, a cam carried by said lever in engaging relation with said star wheel, actuating means for said setting means including therein means engaging the ratchet wheel acting upon said star wheel, a locking member mounted adjacent said hand wheel, means upon said hand wheel engageable thereby, means carried by said actuating means acting upon said locking member, means whereby each disc after it has been set is locked against movement, means whereby the members of said couple may be given relative movement to make an impression from each line of type after it has been set up, and means whereby said type carrying discs may be actuated to distribute the type in said line of type preparatory to the setting of a succeeding line of type.

25. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, word spacing and line justifying mechanisms carried by each disc in operative relation to the adjacent disc, and the other member of which has an impression platen, a locking and alining bar normally disengaged from, but engageable with, the several discs, a proof tape guide adjacent the periphery of said hand wheel, a shaft carrying feed rollers engageable with said tape, a ratchet wheel carried by said shaft, a star wheel co-operating with said ratchet wheel, a second ratchet wheel acting upon said star wheel, a bell crank lever, a spring acting thereon, a proofing hammer carried by one arm of said lever, a cam carried by said lever in engaging relation with said star wheel, actuating means whereby said setting means, with one actuation thereof, is disengaged from a disc which has been set and is brought into the operative relation to the word spacing and line justifying mechanism carried by that disc, and said locking and alining bar is engaged with said disc, means carried by said actuating means engageable with the ratchet wheel acting upon said star wheel, means whereby the members of said couple may be given relative movement to make an impression from each line of type after it has been set up, and means whereby said type carrying discs may be actuated to distribute the type in said line of type preparatory to the setting of a succeeding line of type.

26. A printing machine embodying therein a

- printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, word spacing and line 5 justifying mechanisms carried by each disc in operative relation to the adjacent disc, and the other member of which has an impression platen, a locking and alining bar normally disengaged from, but engageable with, the several discs, a 10 proof tape guide adjacent the periphery of said hand wheel, a shaft carrying feed rollers engageable with said tape, a ratchet wheel carried by said shaft, a star wheel co-operating with said ratchet wheel, a second ratchet wheel acting 15 upon said star wheel, a bell crank lever, a spring acting thereon, a proofing hammer carried by one arm of said lever, a cam carried by said lever in engaging relation with said star wheel, actuating means whereby said setting means, with one actuation 20 thereof, is disengaged from a disc which has been set and is brought into the operative relation to the word spacing and line justifying mechanism carried by that disc, and said locking and alining bar is engaged with said disc, means 25 carried by said actuating means engageable with the ratchet wheel acting upon said star wheel, said star wheel having one-half the number of teeth that the ratchet wheel co-operating therewith has, whereby with the disengagement of said 30 setting means from a disc, said proof tape will be fed and the spring acting upon said bell crank lever will be tensioned, and with the movement of said setting means out of the operative relation to said word spacing and line justifying mechanism, said proofing hammer will be made operative 35 to make an impression of the letter upon said disc brought into the printing line, means whereby the members of said couple may be given relative movement to make an impression from each line of type after it has been set up, and means whereby said type carrying discs may be actuated to distribute the type in said line of type 40 preparatory to the setting of a succeeding line of type.
27. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, and the other member of 45 which has an impression platen, a proof tape guide adjacent the periphery of said hand wheel, a shaft carrying feed rollers engageable with said tape, a ratchet wheel carried by said shaft, a star wheel co-operating with said ratchet wheel, a second ratchet wheel acting upon said star 50 wheel, a bell crank lever, a spring acting thereon, a proofing hammer consisting of a cylinder carried by one arm of said lever, a plunger having a soft head loosely mounted in said cylinder, a cam carried by said lever in engaging relation with said star wheel, actuating means for said setting means including therein means engaging the ratchet wheel acting upon said star wheel, means whereby each disc after it has been set is 55 locked against movement, means whereby the

members of said couple may be given relative movement to make an impression from each line of type after it has been set up, and means whereby said type carrying discs may be actuated to distribute the type in said line of type preparatory to the setting of a succeeding line of type. 5

28. A printing machine embodying therein a printing couple, one of the members of which comprises a rotatable shaft, a hand wheel carried thereby having a sequence of printing characters about the periphery thereof, a plurality of type carrying discs idly mounted upon said shaft, and setting means carried by said shaft engageable with said discs respectively, whereby said discs may be differentially and successively turned to set up a line of type, and the other member of which has an impression platen, a proof tape guide adjacent the periphery of said hand wheel, tape actuating means, a spring pressed lever pivotally mounted adjacent said guide, a proofing hammer carried by said lever, a locking and alining bar, connections between same and said setting means, actuating means for imparting a step by step movement to said setting means and said locking and alining bar including therein a shaft, a sleeve carried by said shaft, a lost motion connection between said sleeve and said shaft, a locking member mounted adjacent said hand wheel, means upon said hand wheel engageable thereby, a cam upon said sleeve acting upon said locking member, a crank handle carried by said sleeve, means carried by said crank handle and operative upon said tape actuating means and said spring pressed lever, means whereby the members of said couple may be given relative movement to make an impression from each line of type after it has been set up, and means whereby said type carrying discs may be actuated to distribute the type in said line of type preparatory to the setting of a succeeding line 20 of type. 25

29. A printing machine embodying therein a printing couple, one of the members of which comprises a rotatable shaft, a plurality of type carrying discs, each having a high tooth, idly mounted upon said shaft, means for turning said shaft, and setting means carried by said shaft engageable with said discs respectively, whereby said discs may be differentially and successively turned to set up a line of type, and the other member of which has an impression platen, actuating means whereby said setting means may be disengaged from each disc after it has been set, means whereby the members of said couple may be given relative movement to make an impression from each line of type after it has been set up, a distributing plate, means whereby movement may be imparted to said plate circumferentially of said discs, means whereby said plate may be moved into and out of engaging relation with the high teeth upon said discs, and a stop bar limiting the movement of said discs by said plate. 45 50 55

30. A printing machine embodying therein a printing couple, one of the members which comprises a rotatable shaft, a plurality of type carrying discs, each having a high tooth, idly mounted upon said shaft, means for turning said shaft, and setting means carried by said shaft engageable with said discs respectively, whereby said discs may be differentially and successively turned to set up a line of type, and the other member of which has an impression platen, actuating means whereby said setting means may be disengaged from each disc after it has been 60 65 70 75

set, means whereby the members of said couple may be given relative movement to make an impression from each line of type after it has been set up, a distributing plate, means whereby movement may be imparted to said plate circumferentially of said discs, means whereby said plate may be moved into and out of engaging relation with the high teeth upon said discs, a stop bar limiting the movement of said discs by said plate, and means whereby said stop bar may be moved into or out of engaging relation with the high teeth upon said discs.

31. A printing machine embodying therein a printing couple, one of the members of which comprises a rotatable shaft, a plurality of type carrying discs, each having a high tooth, idly mounted upon said shaft, means for turning said shaft, and setting means carried by said shaft engageable with said discs respectively, whereby said discs may be differentially and successively turned to set up a line of type, and the other member of which has an impression platen, actuating means whereby said setting means may be disengaged from each disc after it has been set, means whereby the members of said couple may be given relative movement to make an impression from each line of type after it has been set up, a bar movable circumferentially about said discs, a distributing plate having heel and toe portions along opposite edges thereof pivotally mounted upon said bar, means whereby said plate may be moved to bring said heel or said toe portion into and out of engaging relation with the high teeth upon said discs, and a stop bar limiting the movement of said discs by said plate.

32. A printing machine embodying therein a printing couple, one of the members of which comprises a rotatable shaft, a plurality of type carrying discs, each having a high tooth, idly mounted upon said shaft, means for turning said shaft, and setting means carried by said shaft engageable with said discs respectively, whereby said discs may be differentially and successively turned to set up a line of type, and the other member of which has an impression platen, actuating means whereby said setting means may be disengaged from each disc after it has been set, means whereby the members of said couple may be given relative movement to make an impression from each line of type after it has been set up, a bar movable circumferentially about said discs, a distributing plate having heel and toe portions along opposite edges thereof pivotally mounted upon said bar, an actuating crank, openings in one of the supports for said bar, a spring lock member carried by said actuating crank and selectively engageable with said openings, whereby said plate may be moved to bring said heel or said toe portion into and out of engaging relation with the high teeth upon said discs, a pivotal dog, a stop member associated therewith whereby said actuating crank is free to move in one direction, but is actuated in a reverse direction to move both the toe and the heel of said plate out of engaging relation to the high teeth upon said discs, and a stop bar limiting the movement of said discs by said plate.

33. A printing machine embodying therein a printing couple, one of the members of which comprises a rotatable shaft, a plurality of type carrying discs, each having a high tooth, idly mounted upon said shaft, means for turning said shaft, and setting means carried by said shaft engageable with said discs respectively, whereby

said discs may be differentially and successively turned to set up a line of type, and the other member of which has an impression platen, actuating means whereby said setting means may be disengaged from each disc after it has been set, an alining and locking bar, means whereby said alining and locking bar may be disengaged from said discs independently of movement of said setting means, means whereby said bar may be engaged with said discs simultaneously with the disengagement of said setting means therefrom, means whereby the members of said couple may be given relative movement to make an impression from each line of type after it has been set up, a distributing plate, means whereby movement may be imparted to said plate circumferentially of said discs, means whereby said plate may be moved into and out of engaging relation with the high teeth upon said discs, and a stop bar limiting the movement of said discs by said plate.

34. A printing machine embodying therein a printing couple, one of the members of which comprises a rotatable shaft, a hand wheel carried thereby, a plurality of type carrying discs, each having a high tooth, idly mounted upon said shaft each having a keyway therethrough, and a setting bar having a high part engageable with the keyways in the several discs, and a low part substantially flush with the circumference of said shaft, said bar being slidably mounted upon said shaft, whereby said discs may be differentially and successively turned to set up a line of type, and the other member of which has an impression platen, a locking and alining bar normally disengaged from, but engageable with, the several discs, means whereby said setting bar and said alining and locking bar may be connected for simultaneous movement, or disconnected to permit movement of said locking and alining bar independently of said setting bar, actuating means whereby said bars are simultaneously advanced along said shaft to disengage said setting bar from, and engage said alining and locking bar with, each disc as it is set, means whereby the members of said couple may be given relative movement to make an impression from each line of type after it has been set up, a distributing plate, means whereby movement may be imparted to said plate circumferentially of said discs, means whereby said plate may be moved into and out of engaging relation with the high teeth upon said discs, and a stop bar limiting the movement of said discs by said plate.

35. A printing machine embodying therein a printing couple, one of the members of which comprises a single rotatable shaft, a plurality of co-axial type carrying discs idly mounted upon said shaft, means for turning said shaft, and setting means carried by and movable with said shaft engageable with said discs respectively, whereby said discs may be differentially and successively turned to set up a line of type, and the other member of which has an impression platen, actuating means whereby said setting means may be disengaged from each disc after it has been set, means whereby the members of said couple may be given relative movement to make an impression from each line of type after it has been set up, means whereby said type carrying discs may be actuated to distribute the type in said line of type preparatory to the setting of a succeeding line of type, a tank for type cleaning fluid mounted adjacent the periphery of said discs, rollers receiving fluid from said tank, and means whereby said tank may be moved to en-

gage a roller receiving fluid therefrom with the types carried by said discs to simultaneously act upon all type while said discs are being turned, or to hold said rollers out of engaging relation with 5 said types while said discs are being turned to set the type.

36. A printing machine embodying therein a printing couple, one of the members of which comprises a single rotatable shaft, a plurality of co-axial type carrying discs idly mounted upon said shaft, means for turning said shaft, and setting means carried by and movable with said shaft engageable with said discs respectively, whereby said discs may be differentially and successively turned to set up a line of type, and the other member of which has an impression platen, actuating means whereby said setting means may be disengaged from each disc after it has been set, means whereby the members of said couple 10 may be given relative movement to make an impression from each line of type after it has been set up, means whereby said type carrying discs may be actuated to distribute the type in said line of type preparatory to the setting of a succeeding line of type, a tank for type cleaning fluid, pivotal arms supporting said tank adjacent the periphery of said discs, rollers receiving fluid from said tank, a spring acting to normally engage one of said rollers with the type upon said 15 discs to simultaneously act upon all type while said discs are being turned and a spring latch mechanism whereby said tank may be moved so as to hold said rollers out of engaging relation with said type while said discs are being turned 20 to set the type.

37. A printing machine embodying therein a printing couple, one of the members of which comprises a rotatable shaft, a plurality of type carrying discs idly mounted upon said shaft, means for turning said shaft, and setting means carried by said shaft engageable with said discs respectively, whereby said discs may be differentially and successively turned to set up a line of type, and the other member of which embodies therein rocking levers having three arms, 25 one arm of each of which is pivoted adjacent the bed of the machine, a platen bar carried by other arms of said levers, a crank shaft, a pivotal connection between the cranks of said shaft and other arms of said levers, an actuating lever for 30 said shaft, a paper feed cylinder mounted in said lever adjacent said platen, means actuating said paper feed cylinder following the making of each impression to space the lines of succeeding impressions, a locking bar mounted adjacent the 35 periphery of said discs, means normally moving said bar away from said discs, a plurality of hooked spring members carried by said three armed levers, whereby said locking bar will be engaged with said discs prior to the making of an impression, and will receive a starting impulse following the making of the impression, and means whereby said type carrying discs may be actuated to distribute the type in said line of type preparatory to the setting of a succeeding line of type.

38. A printing machine embodying therein a printing couple, one of the members of which comprises a rotatable shaft, a plurality of type carrying discs idly mounted upon said shaft, means for turning said shaft, and setting means carried by said shaft engageable with said discs respectively, whereby said discs may be differentially and successively turned to set up a line of type, and the other member of which embodies therein rocking levers having three arms, one arm of each of which is pivoted adjacent the bed of the machine, a platen bar carried by other arms of said levers, a crank shaft, a pivotal connection between the cranks of said shaft and other arms of said levers, an actuating lever for 10 said shaft, a paper feed cylinder mounted in said lever adjacent said platen, means actuating said paper feed cylinder following the making of each impression to space the lines of succeeding impressions, a locking bar mounted adjacent the 15 periphery of said discs, means normally moving said bar away from said discs, a plurality of hooked spring members carried by said three armed levers, whereby said locking bar will be engaged with said discs prior to the making of 20 an impression, and will receive a starting impulse following the making of the impression, and means whereby said type carrying discs may be actuated to distribute the type in said line of type preparatory to the setting of a succeeding line of type.

39. A printing machine embodying therein a printing couple, one of the members of which has a type setting mechanism comprising a single shaft having mounted thereon a plurality of co-axial independently and differentially rotatable type carrying members, actuating means carried by and rotatable with said shaft and common to all of said members and progressively operative thereon, and means for holding 35 each member stationary after it has been actuated, whereby a single line of type may be set at a time, and the other member of which has an impression platen, means whereby the members of said couple may be given relative movement to 40 make an impression from each line of type after it has been set up, an inking mechanism vertically movable between the member having the type setting mechanism and the member having 45 said platen, an actuating mechanism therefor, connections between said actuating mechanism and the means imparting relative movement to the members of said printing couple including therein means whereby said inking mechanism is brought into and out of the operative relation to the types during the movement of the platen toward said types, and means whereby the type in said line of type may be distributed preparatory to the setting of a succeeding line of type.

BLACKWELL K. MURCHISON.
